H. MANSFIELD

SPARK PLUG

Filed April 3, 1924

INVENTOR
Horace Mansfield,

BY
Harold D. Penney, ATTORNEY

UNITED STATES PATENT OFFICE.

HORACE MANSFIELD, OF YONKERS, NEW YORK, ASSIGNOR OF ONE-HALF TO THOMAS J. CARSON, OF BROOKLYN, NEW YORK.

SPARK PLUG.

Application filed April 3, 1924. Serial No. 703,842.

To all whom it may concern:

Be it known that I, HORACE MANSFIELD, a citizen of the United States, and resident of Yonkers, in the county of Westchester and State of New York, have invented certain new and useful Improvements in Spark Plugs, of which the following is a specification.

My present invention relates to an improvement in high tension spark plugs for igniting the fuel charge in caloric engines, and it has for its principal object a structural arrangement of the terminal portions of the said plug whereby to increase the firing power thereof through the increase in the number of sparks developed by the peculiar surfaces of the coating terminals.

My invention also has for its object that improvement in the associated terminal structures whereby to automatically prevent short circuiting of the terminals and to afford means whereby any bridge of carbon or oil at the terminal gap is immediately broken down and destroyed, thereby leaving the plug entirely free of any deleterious matter that might form thereon and thereby prevent the operation of the plug.

My invention also contemplates the structural arrangement of the coating electrode parts whereby the same may be readily manufactured in an economical and practical manner.

In the drawing herewith, Fig. 1 is a sectional view of my device, taken on the line 1—1 of Fig. 2;

Fig. 2 is a bottom view of my device;

Fig. 3 is a fragmentary view of the bottom portion of my construction showing the action of the coating terminals.

In the construction my plug is substantially made according to present standard practice to the extent that it comprises a base shell 1, having mounted therein an insulating core 2, which may be made of porcelain or other suitable vitreous material, and in the center of which is located a central stem electrode 3 which is held mounted in operation relation in said core by means of a threaded lock nut 4 and for the purpose of permitting the affixed

thereto of the usual wiring, there is also threadedly attached to the upper part of said stem a thumb nut 5.

The porcelain core has the usual shoulder 6 thereon which rests on the shoulder 55 seat 7 within the body of the base 1 and a compression bushing 8 holds the core within the shell in a leakproof manner. A leakproof compression gasket 9 is also utilized at the bottom of the shoulder 6 between said shoulder and the seat 7 in the usual manner.

I will now describe the novel portion of my plug which consists in the constructional details such as is outlined in Fig. 1 at the terminal or electrode end of said plug 60 which is threaded in the usual manner as at 10 to be mounted in an engine cylinder. My novel construction consists in cupping the lower end of the electrode 3 as at 12, and the lower electrode end of the spark 70 plug 11 so that between these two members, which are normally spaced apart, there is located a loose, cooperating floating ball electrode 13, said cupping acting as a socket for the floating electrode ball 13, 75 which the Fig. 1 is shown as resting in the cupping electrode 11 of the base 1.

These cupped members form a substantially spherical contour which is of such a diameter and of such spaced relation that 80 they loosely maintain within their zone the metallic ball 13, preferably made of steel, and in such a manner that the ball is at all times loosely held for permitting rapid vibration and rotation during the operative 85 use of the plug.

It will be ascertained by examining Fig. 2, which is a bottom view of the plug showing the lower plug terminal 11, that is substantially in the form of a bridge across 90 the bottom of the plug, leaving two openings A and B between the side walls of the plug, thereby leaving an open space for the passage of gas into and out of the lower chamber 15 of the plug. The lower electrode or bridge 11 is also provided with an opening 14 therein which is of sufficiently large diameter to expose, as indicated in Fig. 1 a part substantial of surface of the ball to the action of the gases within the 100

cylinder and yet support the ball properly in inoperative position.

It will also be noted that the bridge piece 11 is contoured in such a manner as to form a swell C on both sides so as to allow the formation, midway of said bridge, of the cup which is more fully shown in section in Figs. 1 and 3.

I have discovered in actual practice that, with a floating terminal construction of the type herein disclosed, during the firing action, the lower edges of the cupped terminal 12 discharge a rim of sparks to the ball, which may be resting upon the bridge 11, but should the ball be midway between the two terminals 11 and 12, then there is a double rim of sparks formed between the ball and the two opposing terminals from which it is separated.

I have also ascertained in action that the ball vibrates very rapidly as well as rotates, due to the explosive action of the gases within the cylinder and the vibration of the motor and that as a result the ball during action is never at rest, but is moving about and is rotating at a very high rate of speed, but always within arcing distance of either or both terminals, and this action is entirely due to the rapid vibration of the engine during its operation. This rapid vibratory action keeps the terminal cup edges and the ball clean and this is evidenced by the fact that while the remainder of the plug, as usual, becomes carbonized, the ball and cup edges always retain a bright, clean condition and break down, or throw off all short circuiting conditions and insure a clean, open path for the igniting current to pass therebetween.

I have used this plug in old engines which were so badly worn that lubricating oil, having reached the combustion space of the cylinder, would short circuit an ordinary plug and yet this plug continued to fire and eventually dry out the cylinder, through the formation of carbon, by the burning of such oil and eventually cause the cylinder to become normally dry, fairly compression tight and usefully operative.

It is further obvious that there is also considerable novelty in the manner of the construction of both the stem electrode 3, due to its cup-shaped electrode end 12, as an article of manufacture, and this also applies to the spherically seated electrode bridge 11, in the shell or base 1.

It is obvious that modifications may be made in the details of my device, by one skilled in the art, without avoiding the scope of the invention.

Having thus described my invention, what I claim is:

1. A spark plug comprising a pair of opposed cup-shaped electrodes each provided with an annular contact edge; and a con-

ductive ball loosely retained between and by said edges for intermittent contact therewith and having a radius slightly greater than the inner radius of said annular edges and different from the radius of the faces of the cups to prevent extended contact with the cups except at said edges, whereby packing of carbon in the cups is avoided.

2. A spark plug for internal combustion engines, comprising a pair of opposed cup-shaped electrodes closed against communication with the exterior of the cylinder each provided with an annular contact edge; and a conductive ball loosely retained between and by said edges free during explosion for intermittent contact with said edges.

3. A spark plug for internal combustion engines, comprising a pair of electrodes forming opposed cup-shaped electrodes closed against communication with the exterior atmosphere and each provided with a sharp annular contact edge; and a conductive ball loosely retained between and by said edges free during explosion for intermittent contact therewith and having a diameter slightly greater than the inner diameter of said annular edges and different from the diameter of the faces of the cups to prevent extended contact with the cups except at said edges.

4. A spark plug for internal combustion engines, comprising a pair of electrodes closed against communication with the exterior of the cylinder providing opposed spaced annular coaxial contact faces; and a conductive ball loosely retained between said faces intermittently contactable therewith and free to spin on said faces during explosion.

5. A spark plug comprising an upper electrode provided with a lower annular sparking face; a lower electrode forming a bridge leaving large arcuate openings at the sides of the bridge; the mid part of said bridge being cup-shaped and formed with a central opening; and a conductive ball loosely retained between said face and bridge and contactable therewith.

6. A spark plug comprising a base shell; an insulating core therein; an electrode passing through said core and provided with a cupped lower end forming an annular sparking edge; a thin sheet metal lower electrode member secured to the lower edge of said shell and forming a bridge across the lower part of the shell leaving openings at the sides of the bridge; the mid part of said bridge being formed with a central opening forming an annular sparking edge; and a conductive ball loosely retained between and by said edges and contactable therewith.

7. A spark plug comprising a base shell; an insulating core therein; an electrode passing through said core and provided with a cupped lower end forming an annular spark-

ing edge; a lower electrode member secured to the lower edge of said shell and forming a bridge across the lower part of the shell leaving large openings at the sides of the 5 bridge; the mid part of said bridge being cup-shaped and formed with a central opening forming an annular sparking edge; and

a conductive ball loosely disposed between said edges and contactable therewith.

Signed at New York, in the county of ¹⁰ New York and State of New York, this 2d day of April, A. D. 1924.

HORACE MANSFIELD.
